US00D647511S

(12) **United States Design Patent**
Maier et al.

(10) **Patent No.:** US D647,511 S
(45) **Date of Patent:** ** Oct. 25, 2011

(54) **WIRELESS REMOTE CONTROL**

(75) Inventors: **Ferdinand Maier**, Obertrum am See (AT); **Erwin Weitgasser**, Salzburg (AT); **Detlev Magerer**, Salzburg (AT)

(73) Assignee: **fm marketing GmbH**, Obertrum am See (AT)

(**) Term: **14 Years**

(21) Appl. No.: **29/387,033**

(22) Filed: **Mar. 8, 2011**

(30) **Foreign Application Priority Data**

Sep. 8, 2010 (EP) 001751975

(51) **LOC (9) Cl.** **14-03**

(52) **U.S. Cl.** **D14/218**

(58) **Field of Classification Search** ..... D14/218, D14/455; D13/168; D21/566; D10/104, D10/106; 345/169; 348/14.05, 114, 211.99, 348/734; 340/825.24; 341/22; 455/92, 95, 455/128, 151.1–151.4, 352, 355, FOR. 121; 700/65

(57) **CLAIM**

The ornamental design for a wireless remote control, as shown and described.

DESCRIPTION

FIG. 1 is a perspective view of a wireless remote control showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.
